GAS-FIRED DOOR HEATER

Samuel Scherr, Bernard A. McDermott, and Richard B. Hall, Akron, Ohio, and Andrew Chaloka, Clark, N.J., assignors to Aero-Flow Dynamics, Inc., Linden, N.J., a corporation of New York

Filed Aug. 10, 1966, Ser. No. 3,407

Term of patent 14 years

(Cl. D81—10)

FIGURE 1 is a perspective view from above of a gas-fired door heater embodying our new design;

FIGURE 2 is an end elevational view;

FIGURE 3 is a side elevational view, the opposite side being essentially the same; and

FIGURE 4 is a perspective view from above, similar to FIGURE 1, but the view being from the opposite end.

We claim:

The ornamental design for a gas-fired door heater, substantially as shown.
